[57] **CLAIM**

The ornamental design for a jewelry buffer and polisher head and handle unit, as shown and described.

DESCRIPTION

FIG. 1 is a perspective view as seen from a front, side, and top of the jewelry buffer and polisher head and handle unit according to my new design;

FIG. 2 is a side elevational view thereof;

FIG. 3 is a side elevational view thereof taken from a side opposite that of FIG. 2;

FIG. 4 is a front elevational view thereof;

FIG. 5 is a rear elevational view thereof;

FIG. 6 is a top plan view thereof;

FIG. 7 is a bottom plan view thereof;

FIG. 8 is a perspective view of the jewelry buffer and polisher head and handle unit as in FIG. 1 with a circular polishing tip shown in phantom lines; and,

FIG. 9 is a perspective view of the jewelry buffer and polisher head and handle unit as in FIG. 1 with a pointed polishing tip shown in phantom lines.

The broken lines showing a circular polishing tip and a pointed polishing tip are for illustrative purposes only and form no part of the claimed design.
